[57] CLAIM

The ornamental design for an apparatus for cleaning
drilling mud and fluids, as shown and described.

DESCRIPTION

FIG. 1 is a front elevational view of an apparatus for
cleaning drilling mud and fluids embodying my design
having one hydrocyclone;

FIG. 2 is a top view of the device embodying my design
depicted in FIG. 1;

FIG. 3 is a front elevational view of a device embody-
ing my design having multiple hydrocyclones; and

FIG. 4 is a top view of the device embodying my design
depicted in FIG. 3.
